PILE DRIVER HAMMER COUNTERBALANCE

Thomas H. Settle, Upland, Calif.

Application September 14, 1939, Serial No. 294,945

7 Claims. (Cl. 61—73)

This invention relates to pile driving apparatus and pertains to means for balancing a power operated hammer on a pile.

The present invention has for its primary object to provide a simply constructed but novel counterbalancing means which when used in association with a power operated pile driver, will maintain the pile hammer in the desired position upon the upper end of the pile as it is being driven into position.

Another object is to provide a counterbalancing means for a pile driving hammer which will permit the hammer to be disposed at an angle to the vertical, whereby it may be employed for driving a pile into the ground at an angle, the counterbalancing guide maintaining a vertical position with respect to the hammer.

The invention will be best understood from a consideration of the following detailed description taken in connection with the accompanying drawing forming part of this specification, with the understanding, however, that the invention is not to be confined to any strict conformity with the showing of the drawing but may be changed or modified so long as such changes or modifications mark no material departure from the salient features of the invention as expressed in the appended claims.

In the drawing:

Fig. 1 is a view illustrating the application of the present invention to a pile driving hammer suspended from a supporting boom, showing the means for raising and lowering the counterbalance.

Fig. 2 is a view in elevation of the counterbalance unit per se, looking at the face of the portion to which the hammer is secured.

Fig. 3 is a sectional view on the line 3—3 of Fig. 2.

Referring now more particularly to the drawing, the numeral 1 generally designates a supporting boom from which is suspended by a cable 2, a pile driving hammer 3 of the steam or power operated type, the hammer being shown in position upon the upper end of a pile 4.

In accordance with the present invention the boom is provided with a second pulley 5 over which is run a cable 6 and one end of this cable is connected with a weight 7 which is slidably disposed upon the top of the boom.

At the other end of the cable 6 which is attached to the balance weight 7 is the hammer counterbalancing unit embodying the present invention and this consists of a T-beam 8 which has one end connected to the cable 6 and to the

head 9 of which is slidably connected a plate 10. The plate 10 is of slightly greater length than the hammer 3 and is disposed longitudinally of the hammer as shown, and on its back face are formed the opposed guides 11 between which the edges of the head portion of the beam 8 slidably engage.

At its lower end the head 9 of the supporting beam 8 has the laterally extending stop ears 12 which engage across the ends of the guides 11 and limit downward movement of the plate 10 on the beam 8.

Secured upon the longitudinal center of the plate 10 at the bottom thereof, by a bolt 13, is a foot bracket 14. Across the top of the plate 10 upon the hammer side or face thereof, is disposed a rocker beam 15 which is in the form of an angle iron, one flange of which is provided with suitable apertures 16, which correspond with apertures, not shown, in the plate 10 to receive securing bolts 17. By these bolts the beam 15 is secured across the top of the plate 10 with one flange projecting forwardly and having spaced parallel relation with the foot bracket 14.

As shown in Fig. 1, the hammer 3 is disposed between and secured to the bracket 14 and beam 15, and thus it will be seen that when the hammer is in place upon a pile, the counterbalance guide will be disposed vertically at its side. When the pile is to be driven into the ground at an angle, then the bolts 17 are removed and the hammer is rocked on the foot bracket 14 to the desired angular position and one or both of the bolts 17 may be replaced to hold the hammer in the angular relation with respect to the beam 8. Fig. 2 illustrates how the plate 10 may be oscillated to an angular position for keeping the hammer at an angle while the supporting guide maintains its vertical position.

When the hammer is lifted from the pile and drawn upwardly toward the boom, the balance weight 7 for the counterbalancing unit will raise this unit with the hammer and as the hammer is moved downwardly into position on a pile, the plate 10 will be limited in its downward movement with respect to the beam 8 by the ears 12 so that the unit will be drawn down into the proper working position and the unit will function to maintain the hammer upright while it is in operation for driving the pile into the ground.

It has been previously stated that the hammer 3 is disposed between and secured to the bracket 14 and beam 15. The means by which the connection may be made between these parts may be of any suitable character, but it is preferred that

these parts 14 and 15 be welded to the hammer 3 so that there will be no possibility of the hammer and the guide becoming separated.

What is claimed is:

1. In pile driving apparatus, including a boom and a power driven hammer suspended therefrom, a bar suspended by one end from said boom, a plate slidably connected with said bar, means coupling said hammer with said plate, means limiting the sliding movement of said plate downwardly on said bar, and means supported by the boom and connected with the bar for effecting the raising of the bar and the plate with the hammer.

2. In pile driving apparatus, including a boom and a power hammer suspended therefrom, a T-beam, cable means connecting an end of said beam with the boom facilitating vertical movement of the beam with respect to the boom, a plate slidably attached to the head of the T-beam, means limiting the movement of the plate on the T-beam, and means securing said hammer to one side of said plate.

3. In pile driving apparatus, including a boom and a power hammer suspended therefrom, a T-beam, cable means connecting an end of said beam with the boom facilitating vertical movement of the beam with respect to the boom, a plate slidably attached to the head of the T-beam, means limiting the movement of the plate on the T-beam, and means securing said hammer to one side of said plate, said means being so constructed and arranged that the hammer may be oscillated to an angular position with respect to the plate and beam.

4. In apparatus of the character described, a power driven hammer, an elongated beam, a plate disposed against a side of the hammer, means slidably coupling said plate with said beam, means securing the hammer to the plate, the hammer and plate being designed to be independently suspended, and means for altering the position on the plate of the securing means for the hammer for securing the hammer at an angular position with respect to the plate.

5. In apparatus of the character described, a power driven hammer, a T-beam, a plate disposed longitudinally of the T-beam and against the head of the same, guide means carried by the plate and slidably coupling the same with the head of the T-beam, bracket means oscillatably

attached to said plate adjacent an end thereof, said beam at the end remote from said bracket means being formed to facilitate its suspension by a cable, and a beam secured transversely of the plate adjacent the end of the plate remote from said bracket means, the hammer being secured vertically between the bracket means and the last mentioned beam and the hammer being adapted to be suspended independently of the first beam.

6. In apparatus of the character described, a power driven hammer, a T-beam, a plate disposed longitudinally of the T-beam and against the head of the same, guide means carried by the plate and slidably coupling the same with the head of the T-beam, bracket means oscillatably attached to said plate adjacent an end thereof, said beam at the end remote from said bracket means being formed to facilitate its suspension by a cable, a beam secured transversely of the plate adjacent the end of the plate remote from said bracket means, the hammer being secured vertically between the bracket means and the last mentioned beam and the hammer being adapted to be suspended independently of the first beam, and stop means forming an integral part of the T-beam for limiting the longitudinal movement of the plate in one direction thereon.

7. In apparatus of the character described, a power driven hammer, an elongated beam, a plate disposed against a side of a hammer, means slidably coupling said plate with said beam, a bracket member secured to the side of the plate opposite from the beam for engaging and supporting the hammer, said bracket member being mounted for oscillation on an axis extending transversely of the plate and beam, a clamping beam extending transversely of said plate at the opposite end of the hammer from said bracket and engaging the top of the hammer and cooperating with the bracket to maintain the hammer secured to the plate, and means securing the clamping beam to said plate which is so constructed and arranged that the clamping beam may be shifted across the adjacent face of the plate along an arcuate path having as its center the center of oscillation of said bracket to secure the hammer in a selected angular position with respect to the plate and the said elongated beam.
